UNITED STATES PATENT OFFICE.

WILLIAM VAN SLOOTEN, OF NEW YORK, N. Y.

MINER'S COMPASS.

SPECIFICATION forming part of Letters Patent No. 635,606, dated October 24, 1899.

Application filed April 3, 1899. Serial No. 711,497. (No model.)

To all whom it may concern:

Be it known that I, WILLIAM VAN SLOOTEN, a citizen of the United States, residing in the city of New York, in the borough of Brooklyn and State of New York, have invented certain new and useful Improvements in Miners' Compasses, of which the following is a specification.

This invention relates to certain improvements in miners' compasses, so that the outcrop of veins of ore, beds of coal, &c., can be readily and accurately determined upon the surface of the ground and readily traced thereon or its proper place indicated thereon in case said outcrop is hid by an overburden of rock or vegetation or other material; and the invention consists of an ordinary miner's compass and of an attachment arranged at right angles to the bar carrying the sights and consisting of a semicircular graduated frame attached to the needle-box of the compass, a slide-piece guided on said frame, and an auxiliary sight-bar pivoted to said slide-piece and provided with auxiliary sight-pieces or a telescope, said auxiliary sight-pieces or telescope in connection with the graduated frame permitting the tracing of the outcrops of veins or beds, as will be fully described hereinafter and finally pointed out in the claims.

In the accompanying drawings, Figure 1 represents a side elevation of a miner's compass with my improved attachment. Fig. 2 is a plan of the same. Fig. 3 is a side elevation; and Figs. 4 and 5 are respectively a side view showing the connection of the auxiliary sight with the semicircular frame attached to the needle-box and a vertical transverse section on line 55, Fig. 4, said figures being drawn on a larger scale.

Similar letters of reference indicate corresponding parts.

Referring to the drawings, A represents the box of an ordinary surveying-compass, such as is used by surveyors, mining engineers, and others. The box A incloses the magnetic needle B and is provided with folding sight-pieces C C, which are attached to diametrically opposite points of the box, said sights being provided with the usual slits for making observations. The needle plays over a graduated circle divided, as usual, into three hundred and sixty degrees. The box is con-

nected by a screw-socket D with a Jacob's staff E, said socket being provided with a ball-and-socket joint D', so as to permit the adjustment of the box by means of the usual levels into horizontal position. 55

The compass so far described is well known and forms no part of my invention.

At right angles or equatorially to the line of sight of the compass is arranged a semicircular frame F, that extends diametrically or equatorially across the box, said frame F being provided at its ends with recesses f and lugs f', the latter extending below the box, 65 and with fastening-screws f², by which the frame is secured to the box accurately in line with the diametrical or equatorial line drawn through the numbers "90" at each side of the graduated circle of the box A. The semicircular frame F is provided with graduations at both sides, each quadrant of the same being divided into ninety degrees, both graduations beginning at the lower ends and running up to the center of the frame. Outside 70 of the graduations the frame F is provided at each side with a guide-groove f³, in which is guided a slide-piece F', that is secured by means of set-screws f⁴ into the grooves f³ and provided with an oblong opening corresponding to the cross-section of the frame F, so that the slide-piece can be moved readily over the same and be adjusted at any desired point on its graduation. The lower part of the slide-piece F' is provided with a rectangular side 75 opening and an index, so as to permit the convenient reading off of the graduations on each side of the frame F. The slide-piece F' is provided with a recess g in its upper end, to which is pivoted, by means of a lug g' and clamping-screw g², a supporting-piece g³, having a pin g⁴. To this pin is applied, by a sleeve g⁵ and set-screw g⁶, a bar G, that is provided at its ends with auxiliary stationary or folding sights G', 85 which are secured by suitable set-screws g⁷ at right angles to the bar G. The bar G, with its auxiliary sights G', is supported on the slide-piece at right angles to the frame F. 90

When the direction or strike and dip of the vein or bed of coal, ore, &c., at any point of outcrop is to be taken, the instrument is first placed in horizontal position, carefully leveled, and then its sights pointed in the angle of strike of the vein or bed, and then the slide-

piece, with its auxiliary sights or telescope, is moved over the frame and placed in plane of the dip and the outcrop of the vein or bed sighted, after which the outcrop at all points on the 5 surface can be laid off and traced if the vein or bed preserves a regular strike and dip. The outcrop of vein or bed can be thus traced as far as may be deemed correct or convenient, thus saving much work as compared with 10 the ordinary methods heretofore employed for determining the outcrop on the surface.

My improved attachment is designed to facilitate the work of the mining engineer in determining the outcrops of veins and beds and 15 forms a very useful and time-saving attachment to the ordinary miner's compass, to which it can be readily applied, so that the compass can be used at the same time for determining the angle or dip of veins of ore or 20 beds of coal, if necessary, but for determining more particularly the outcrop at some point, so as to trace it then readily on the surface.

Having thus described my invention, I claim as new and desire to secure by Letters Patent—

1. The combination with an ordinary miner's compass, of a semicircular graduated frame secured thereto at right angles or equatorially to the sights of the compass, a slide- 30 piece guided on said frame, and an auxiliary bar and sights or telescope supported on said slide-piece, substantially as set forth.

2. The combination, with an ordinary miner's compass, of a semicircular graduated

frame secured at right angles or equatorially 35 to the sights of the compass on the needle-box of the compass, said frame being provided with a guide-groove on each side, a slide-piece guided along said frame, set-screws extending through the slide-piece into said guide- 40 grooves, and an auxiliary bar supported on said slide-piece at right angles to said frame and carrying sights or a telescope, substantially as set forth.

3. An attachment for miners' compasses, 45 consisting of a semicircular graduated frame, means for attaching it to the needle-box of the compass, a slide-piece guided along said graduated frame, and an auxiliary bar having sights and supported on said slide-piece at right angles to said frame, substantially as set forth.

4. An attachment for miners' compasses, composed of a graduated semicircular means 55 at the lower end of said frame for attaching it to the needle-box of the compass, said frame having guide-grooves, a slide-piece guided in said grooves, means for clamping said slide-piece to said frame, and an auxiliary bar supported in said slide-piece at right angles to said frame and provided with sights or a telescope, substantially as set forth.

In testimony that I claim the foregoing as my invention I have signed my name in presence of two subscribing witnesses.

WILLIAM VAN SLOOTEN.
